DESIGN FOR A SHOE

Rose Gruensfelder, St. Louis, Mo.

Application March 24, 1939, Serial No. 83,804

Term of patent 7 years

To all whom it may concern:

Be it known that I, Rose Gruensfelder, a citizen of the United States, residing at the city of St. Louis, State of Missouri, have invented a new, original, and ornamental Design for a Shoe, of which the following is a specification, reference being had to the accompanying drawing, forming part thereof.

The figure is a perspective view of a shoe showing my new design. The distinguishing feature of the design is a vamp which is constructed of stretchable leather quilted to form diamond shaped tufts.

I claim:

The ornamental design for a shoe, as shown and described.

ROSE GRUENSFELDER.
